UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR CATALYTICALLY TREATING HYDROCARBON OIL

Application filed August 16, 1922, Serial No. 582,296. Renewed September 1, 1928.

This invention relates to improvements in apparatus for catalytically treating hydrocarbon oil to produce relatively low boiling point oil such as gasoline and the like from higher boiling point oil. The process is preferably operated continuously and under a substantial pressure.

The single figure is a diagrammatic side elevational view of the apparatus with parts in section.

Referring to the drawing, the oil to be treated is introduced from any convenient extraneous source through the line 1, and is charged by means of the pump 2 through the line 3 controlled by the valve 4, to a still 5 mounted in a furnace 6, which is preferably heated by gas burner 7. In the upper portion of the still is positioned a rotating cylinder 8 supported by suitable bearings 9 at each side of the still so that the cylinder which is mounted upon a shaft 10 may be rotated by means of the pulley 11 from any suitable source of power not shown. It may be necessary to water-jack or otherwise cool the bearings in the still which support the shaft 10, as the temperatures will be high in this portion of the apparatus. The showing of the water-jacketing equipment for bearings has been omitted from the drawing for the purpose of simplifying the showing.

The oil is maintained at a level in the still and there is introduced thereto through the pipe 12, pump 13, and line 14, a catalytic substance such as aluminum chloride. This substance is introduced into the bottom of the still by means of a circular, perforated pipe or rose 15, which serves to cause the catalytic substance to be forced into and to percolate or bubble up through the body of the oil. During the introduction of the catalytic substance the oil is heated, the vapors evolved passing off to the dome 16 positioned at the top of the still and into the vapor line 17 regulated by valve 18. The oil vapors are directed through the line 17 to a condenser coil 19 positioned in the condenser box 20 being discharged from the coil through a line 21 regulated by valve 22 to the receiving tank 23. The receiving tank 50 is equipped with a pressure relief valve 24 a

liquid draw off valve 25, pressure gauge 26 and liquid level gauge 27, this latter equipment being important in the controlling of the pressure maintained upon the apparatus, and the valve 25 serving to draw off the distillate formed. Into the bottom of the still is tapped a residual draw off line 28 which is regulated by valve 29 whereby the heavier residual substances may be withdrawn from the still as desired.

In operation the oil to be treated is charged, as explained, and maintained at a level in the still. The catalytic substance is introduced in regulated quantity while the oil is heated to a cracking temperature and the pressure of the evolved vapors maintained to produce the best cracking conditions for conversion. During the treatment of the oil, besides the vaporization of the hydrocarbon substances, there will be a subliming of the catalytic material, and portions thereof carried with the hydrocarbon vapors into the top of the still. It is for the purpose of precipitating the catalytic substance that the cylinder or roller 8 is positioned in the still. The cylinder 8 is cooled by water introduced through the end of the shaft 8 by a pipe shown at 30. The passage of this water through the cylinder is retarded by baffle plates shown at 31, so that the surface of the cylinder is cooled during its passage therethrough and the travel of the water retarded by the alternate positioning of the baffle plates. The water is discharged through the opposite end of the cylinder through the line 32. Thus when the vapors arise from the oil body and come in contact with the cooled rotating cylinder, both the higher boiling point oils and the aluminum chloride will be separated from the vapors, a part of the catalytic substance collecting upon the surface of the cylinder and removed therefrom by a scraper or blade 33, which is positioned at the top of the still and in contacting relation with the cylinder 8.

Thus the precipitated catalytic substance will be scraped from the surface of the cylinder and will fall back into the oil where it will again take part in the reaction or conversion taking place.

The oil vapors which rise into the dome 16 in the top of the still pass off through the line 17, and after being subjected to a condensing action in the coil 19, are collected as liquid distillate in the receiving tank 23.

5 It is a well known fact that the cracking of hydro-carbon oil in the presence of a catalytic material such as aluminum chloride produces a higher grade distillate, but difficulty has been experienced in preventing the catalytic substance from passing over with the vapors to the receiver where it must be subsequently separated from the oil and returned to be reused in the conversion zone.

10 15 By the use of a cooled cylinder as shown, the greater part of the vaporous catalytic substance can be separated out and returned to the oil body, and in addition to this feature the higher boiling point hydrocarbon oils are prevented from passing over to the receiver with the lighter distillates.

20 The temperature of the cooling cylinder may be regulated by the water which is permitted to flow therethrough. By carefully 25 controlling the temperature and pressure conditions in the system from 30% to 60% of high grade distillate can be obtained from mid continent gas oil of approximately 32° Baumé operating under pressures ranging 30 from 50 to 300 lbs. The distillate is of high quality and ranges in Baumé from 48° to 52°.

35 I claim as my invention:

An apparatus for catalytically treating hydrocarbon oils in combination with a still, 40 of cooling means positioned within the vapor space of the still, means for charging oil and means for charging catalytic material to the still, means for removing precipitated catalyst from the cooling means, and means for condensing the vaporous constituent.

GUSTAV EGLOFF.
